(57) **CLAIM**

We claim the ornamental design for an electronic device stand, as shown and described.

DESCRIPTION

FIG. 1 is a first perspective view of an electronic device stand.

FIG. 2 is a second perspective view of the electronic device stand shown in FIG. 1.

FIG. 3 is a third perspective view of the electronic device stand shown in FIG. 1 in a second configuration.

FIG. 4 is a front view of the electronic device stand shown in FIG. 1.

FIG. 5 is a rear view of the electronic device stand shown in FIG. 1.

FIG. 6 is a first side view of the electronic device stand shown in FIG. 1.

FIG. 7 is a second view of the electronic device stand shown in FIG. 1.

FIG. 8 is a top view of the electronic device stand shown in FIG. 1; and,

FIG. 9 is a bottom view of the electronic device stand shown in FIG. 1.

The broken lines having equal segments represent portions of the article that form no part of the claimed design.
